UNITED STATES PATENT OFFICE.

STEPHEN F. BRIGGS, OF MILWAUKEE, WISCONSIN, ASSIGNOR TO BRIGGS & STRATTON COMPANY, OF MILWAUKEE, WISCONSIN, A CORPORATION OF WISCONSIN.

IGNITER FOR GAS-ENGINES.

1,050,799.

Specification of Letters Patent. Patented Jan. 21, 1913.

Application filed March 28, 1910. Serial No. 552,013.

To all whom it may concern:

Be it known that I, STEPHEN F. BRIGGS, residing in Milwaukee, in the county of Milwaukee and State of Wisconsin, have invented new and useful Improvements in Igniters for Gas-Engines, of which the following is a description, reference being had to the accompanying drawings, which are a part of this specification.

10 This invention has for its object to provide an igniter of the induction coil type with a switch for the primary circuit which will be closed mechanically by the operation of the engine and will be opened electrically 15 by means depending upon the closing of the switch, thus producing a closed circuit of momentary duration and independent of the speed of the engine and also obviating the possibility of the circuit remaining closed 20 when the engine stops.

Another object is to utilize the magnetic effect of the induction coil itself to effect the opening of the primary circuit switch.

Another object of the invention is to improve upon details of construction of 25 igniters of this type.

In the accompanying drawings I show an exemplifying structure embodying the invention, but it is to be understood that the 30 invention is capable of embodiment in different forms.

With the above and other objects in view the invention consists in the construction or 35 relative arrangement of certain parts and in combinations thereof as pointed out in the claims.

Referring to the drawings: Figure 1 is a 40 sectional view of an igniter embodying the present invention, the cam being magnetically withdrawn from engagement with the movable switch contact to break the primary circuit; Fig. 2 is a plan view thereof with the cap removed, showing the switch contacts in their closed position; Fig. 3 is a 45 similar view with the switch contacts magnetically released; Fig. 4 is a detail sectional view showing the construction of the cam parts and the relation of the cam to the movable switch contact at the time of closing 50 the primary circuit; Fig. 5 is a detail perspective view of the cam parts and their casing, the latter being sectioned; and, Figs. 6 to 11 are diagrams of modifications of this 55 invention.

In these drawings 10 indicates a casing

which is intended to be rigidly connected to the engine base or other suitable support and has a distributor block 11 of insulating material fitting in its upper end. A rotor is journaled within the casing and contains the 60 spark coil in an insulating cylindrical shell 12, said spark coil comprising the core 13, the primary winding 14 and the secondary winding 15.

The lower journal mounting for the rotor 65 consists of a metal plate 16 secured to the insulating shell 12 and carrying a trunnion 17 which is journaled in a ball bearing 18 at the bottom of the casing 10 and is intended for connection with the cam shaft of the 70 engine. The upper journal mounting for the rotor comprises a tubular trunnion 19 mounted on the upper end of the insulating shell 12 of the rotor, preferably by having 75 annular flanges 20 molded into the hard rubber or other insulating composition of which said shell is made, said trunnion 19 being journaled in a ball bearing 21, threaded in a flanged bushing 22, which in turn is threaded into the distributing block 11.

An annular plate 23 is mounted to turn on top of the distributor block 11 by fitting around the flange of the bushing 22, this movement being accomplished by means of an arm 24 projecting radially from the plate 80 23 and adapted for connection with the spark advancing and retarding mechanism 85 of the engine, and being limited by screw stops 25 projecting from the distributor block and riding in arc shaped slots 26 of the 90 plate 23. The plate 23 has mounted on it the switch contacts which control the primary circuit of the induction coil, the stationary contact 27 being insulated from the plate 23 and having a screw contact point 95 28 for adjustment, and the movable contact 29 being pivotally mounted on a post or stud 30 projecting from the plate 23 with a leaf spring contact point 31 to engage the screw contact point 28 and a curved finger 100 32 to be engaged by the cam of the rotor for closing the contacts and a spring 33 for retracting the movable contact when it is disengaged from the cam.

The cam carried by the rotor for engaging the contacts is one which is under the influence of the magnetic attraction of the core 13 of the spark coil so as to be automatically withdrawn from its operative position immediately upon effecting the en- 110

2
gagement of the contacts. This cam may be variously constructed and arranged, but preferably comprises a cam member 34 clamped upon a stem 35 between a shoulder thereof and a spacing collar 36 by means of a nut 37 threaded on the end of the stem, said cam member being provided with as many equally spaced radially projecting cam lugs 38 as there are cylinders to the engine. The lugs 38 pass out through slots 39 in the upper end of the tubular trunnion or cam casing 19 and are slideable vertically therein to occupy a position in the same plane as the finger 32 of the movable contact, so as to engage therewith during the rotation of the rotor, or to occupy a position below said plane where they will escape the finger 32. The stem 35 is normally held in its upper position with spring pressure with the cam lugs 38 in the plane of the finger 32 of the movable contact by means of a light coil spring 40 surrounding the stem and bearing at its upper end against the cam member 34 and at its lower end against a cup shaped spring seat 41 which also surrounds the stem 35 and which has ears 42 at its upper edge bent outwardly to engage the lower ends of the slots 39. The lower end of the stem 35 is preferably enlarged to form a head 43 for attraction by the core 13 of the induction coil which becomes energized as a magnet upon the primary circuit of the induction coil being closed. The head 43 of the cam stem 35 is made of iron to constitute the armature for the magnet formed by the induction coil and the tubular trunnion or cam casing 19 is made of brass or other non-magnetic material so as to not interfere with the influence of the magnet upon its armature. The head 43 may be either loosely fitted within the bore of the tubular trunnion 19, so as to avoid the formation of a dash pot that would tend to retard its motion, or it may be provided with a vent opening 44 therethrough having the same effect. The end of the downward stroke of the cam stem is cushioned by providing a disk of cork or leather or other suitable yielding material 45 in the bottom of the tubular trunnion 19, and the upward movement of the cam stem is limited and cushioned by its upper end striking against a similar disk 46 contained within a screw cap 47 which is threaded on the upper end 55 of the tubular trunnion.

60 A metal shell 48 forms a cover for the contact mechanism and is held in place by fitting upon a stud 49 standing up from the plate 23 and a stud 50 standing up from the insulated stationary contact 27, the latter being protected from contact with the cover by means of an insulated bushing 51 surrounding it. The stud 49 has a nut 52 threaded thereon and the stud 50 has a nut 53 threaded on it to clamp the cover in

place and to form binding posts for the terminals 54 of the condenser 55 which is contained in the space between the rotor and the casing 10.

One end of the primary winding is connected with one end of the secondary winding, as usual, at 56 and is grounded on the frame by connecting with the metal plate 16 of the lower trunnion, there being a spring brush 57 on the casing 10 and bearing against the plate 16 to insure a perfect contact for this ground frame connection. The other end of the primary winding is connected at 58 with the tubular trunnion 19 which is in metallic engagement through the bearing and otherwise with the parts forming the casing for the contact mechanism, including the plate 23 and the movable contact 29. Thus it will be seen, that when one terminal, 75, of the battery 76 is grounded on the frame, as usual, and thereby is in connection with the grounded end of the primary coil, and the other terminal 77 of the battery is connected with the binding post formed by nut 53, the primary circuit will be closed through the primary winding of the induction coil upon the contact points 31 and 28 becoming engaged and will be broken upon their separation. While one end of the secondary winding 15 of the induction coil is grounded on the frame of the engine through the connection of the casing 10 therewith, as previously described, the other end thereof is connected at 59 with a tubular sleeve 60 near the upper end of the cylindrical shell 12 of the rotor, which sleeve contains a spring pressed distributor brush 61, sweeping around the interior of the distributor block 11 and coming into engagement with distributor segments 62 embedded in said distributor block. These segments 62 are connected by lead wires 63 with tubular sockets 64 embedded in the side of the distributor block and which are adapted for connection with the plugs of the usual high tension leads 78 which connect with the spark plugs 79 of the several cylinders of the engine. There being one of the contact segments 62 for each cylinder of the engine, it is obvious that at the time of the operation of the switch contacts by means of the cam, the secondary current from the induction coil will traverse the spark plug connection leading from whichever contact segment 62 the brush 61 then engages. Thus the secondary circuit of the induction coil constitutes an ignition means by which ignition is produced in that cylinder of the engine which has its piston in position for the explosion.

125 In operation, instead of the cam operating upon the movable contact to effect the closing of the primary circuit a variable length of time, depending upon the speed of movement of the cam, as would be done 130

if the cam remained fixed with relation to the rotor, said cam, immediately upon closing the primary circuit, is drawn downwardly by the attraction of the induction coil upon the head 43, and is thus moved out of the plane of engagement with the movable contact 30, so as to permit said contact to be retracted by its spring 33 and break the primary circuit. The period of contact at slow speed is therefore much reduced from what it would be if the cam were not moved out of its operative relation with the movable contact immediately upon the closing of the primary circuit.

Although the opening of the primary circuit relieves the cam of the attraction by the magnet, the alacrity with which the circuit is opened will ordinarily find the cam lug 38 still beneath the finger 32 of the movable contact so that the cam does not rise to its normal position under the influence of its spring 40 until such cam lug has moved sufficiently to free it from the finger, when the spring returns the cam to its upper position ready to engage the contacts by means of the next cam lug. It is possible that when the engine is operated at an exceedingly high speed the instantaneous period of engagement of the cam lugs 38 with the movable contact will be of such short duration that the magnetic effect will be insufficient to draw the cam from its normal upper position before the cam lug passes the finger, but this is an advantage rather than a disadvantage, for at such times it is desirable to have the period of contact relatively longer than at slow speeds.

Besides effecting a contact of uniform and momentary duration at different speeds of the engine, the present invention avoids the possibility of the engine being brought to a stop in a position in which it will leave the primary circuit closed, for should the engine be stopped with the parts in the position shown in Fig. 2, the closed primary circuit would cause the attraction of the cam by the core of the induction coil so as to withdraw said cam from its engagement with the movable contact and thereby permit the contact to move away from the stationary contact under the influence of its spring to open the primary circuit, and the parts would remain in this position until the engine is again started.

It is obvious that this invention is not limited to the specific means shown for utilizing the magnetic influence of the induction coil for breaking the primary circuit after it has been closed by mechanical means, or to the magnetic influence being that of the induction coil, but that various other means may be employed for accomplishing the object sought without departing from this invention and other electro-

magnetic means in the primary circuit may be employed for magnetically breaking the circuit which is mechanically closed. I therefore desire it to be understood that this invention is not limited to any specific form or arrangement of parts except in so far as such limitations are specified in the claims.

As illustrating in diagram some of the various modifications comprehended by this invention and included within the terms of the claims reference is made to Figs. 6 to 9 inclusive.

In Fig. 6 an engine operated cam 80 engages an armature 81 of the magnet 82 and thereby closes the magnet circuit, whereupon the magnet becomes energized and attracts the armature and moves it away from the cam to break the circuit. Insulating means on the cam or the armature may be provided to prevent vibration. The induction coil may be omitted in this form, the cam and armature constituting a "make and break" device located in the cylinder, or an induction coil may be provided with its primary circuit controlled by the engagement of the cam and the armature, either by including the primary winding in the magnet circuit shown or in another circuit in a manner similar to the connection illustrated in Fig. 7.

In Fig. 7 the cam 83 engages a contact 84 and moves it into engagement with the armature 85 of magnet 86, thus closing the magnet circuit 87 and also the primary circuit 88 of an induction coil 89. With this construction also, the ignition contact is made mechanically and is broken electrically through a circuit established by the primary switch contacts. In such construction the batteries for the magnet circuit and the primary circuit of the induction coil may be connected in multiple as shown.

Fig. 8 represents substantially the same system as shown in Fig. 7 with the magnet 86 contained in the primary circuit 88 of the induction coil 89, the operation remaining the same.

Fig. 9 more closely resembles in diagram the preferred construction illustrated in Figs. 1 to 5, wherein the magnet 86 of the system shown in Fig. 8 consists of the induction coil 89.

In Fig. 10 the rotor trunnion 92 is provided with as many flat surfaces 93 as there are cylinders to the engine and a spring actuated contact 94 bearing on the trunnion is permitted by these flat surfaces 93 to move its contact point into engagement with a stationary contact point 95 to close the primary circuit 96 of the induction coil 97, the core thereof constituting the trunnion 92 of the rotor, though shown separate in the diagram for clearness of illustration. A bell crank lever 98 stands close to the trunnion 92 and constitutes the armature for the

1 magnet formed by the induction coil and is attracted to the trunnion 92 when the primary circuit is closed. In moving toward the trunnion 92 it swings its upper end 5 against a cam 99 on the contact 94 which effects the disengagement of the contacts to open the primary circuit, and then the bell crank armature 98 returns to its normal position, preferably through the action of the flat surfaces 93 of the trunnion 92 thereon.

10 In Fig. 11 a modification of the construction of the cam end of the rotor is illustrated, wherein a trunnion 100 is mounted on the insulating shell 101 of the induction coil and has the cam stem 102 slidably mounted in it with the head 103 forming the armature for the magnet and contained within the end of the primary winding 104 of the induction coil so that said primary winding acts upon it as a solenoid to give a greater magnetic effect than when the attraction of the core 105 is alone relied upon. The movements of the armature stem are cushioned as before, and the cam 106 is secured to the end of the stem 102 by means of a nut 107, the spring 108 being confined within annular grooves in the end of the trunnion 100 and the bottom face of the cam 106 respectively. The cam is prevented 25 from turning by having a pin 109 passing through an opening therein, said pin being threaded in the trunnion 100 and being bent over to the axis of the rotor where it is provided with a lug 110 engaged by a contact spring 111 on the cover 112 for maintaining electrical connection therewith. With this form of the invention a greater magnetic effect is accomplished and less resistance is imposed upon the movements of the cam.

30 40 What I claim as new and desire to secure by Letters Patent is—

1. An igniter for gas engines, comprising switch contacts, engine driven means engaging the switch contacts with each other at intervals, an electro magnet for disengaging the switch contacts controlled by the engagement of said switch contacts and an ignition circuit including the switch contacts and controlled thereby.
2. An igniter for gas engines, comprising switch contacts, an engine driven cam engaging the switch contacts with each other at intervals, an electro magnet for disengaging the switch contacts controlled by the engagement of said contacts, and an ignition circuit including the switch contacts and controlled thereby.
3. An igniter for gas engines, comprising switch contacts, engine driven means for closing the switch contacts, an electro magnet for disengaging the switch contacts controlled by the engagement of said contacts, said electro magnet constituting an induction coil, and a spark plug connected with the secondary circuit of the induction coil.

4. An igniter for gas engines, comprising switch contacts, an engine driven cam normally in position for engaging and closing the switch contacts at intervals but movable from said position, an electro magnet energized by the closing of the switch contacts and adapted to withdraw the cam from its operative relation with the switch contacts and thereby cause the opening of the switch contacts, and ignition means controlled by the closing of the switch contacts. 70

5. An igniter for gas engines, comprising switch contacts, an engine driven cam normally in position for engaging and closing the switch contacts at intervals but movable from said position, and an induction coil having its secondary circuit forming an ignition means and its primary circuit controlled by the switch contacts, said induction coil constituting a magnet for withdrawing the cam from its operative position with relation to the switch contacts to cause the opening of the switch contacts. 80

6. An igniter for gas engines, comprising a switch contact, an induction coil rotatably mounted and adapted to be connected with the engine to be driven thereby, and a cam carried by the induction coil in position to normally engage and close the switch contact but movable from said position, the primary circuit of the induction coil being controlled by the switch contact, said induction coil constituting a magnet to be energized by the closing of the switch contact and adapted to withdraw the cam from its operative relation with the switch contact, the secondary circuit of the induction coil constituting an ignition means. 90

7. An igniter for gas engines, comprising a rotatably mounted induction coil adapted to be driven by the engine, a cam carried by the induction coil, a switch contact engaged by the cam for closing the primary circuit of the induction coil, and movable means attracted by the induction coil when it is energized for disengaging the cam and the contact for breaking the primary circuit, the secondary circuit of the induction coil constituting an ignition means. 105

8. An igniter for gas engines, comprising a rotatably mounted induction coil driven by the engine, a spring pressed axially movable cam carried by the induction coil, a switch contact engaged by the cam for closing the primary circuit of the induction coil, and an armature connected with the cam and adapted to be attracted by the core of the induction coil when the induction coil is energized by the closing of the primary circuit for withdrawing the cam from its engagement with the switch contact and thereby opening the primary circuit, the secondary circuit of the induction coil constituting an ignition means. 110

9. An igniter for gas engines, comprising 120

- a rotatably mounted induction coil adapted to be driven by the engine, a cam slidably mounted on the induction coil and turning therewith, a spring for holding the cam in a 5 normal position, a switch contact in position to be engaged by the cam when the cam is in its normal position and adapted to be swung thereby, a stationary switch contact to be engaged by the swinging contact, said 10 switch contacts being included in the primary circuit of the induction coil for closing the same, and an armature attracted by the magnet formed by the core of the induction coil, and connected with the cam for 15 moving the cam out of its engagement with the swinging switch contact and thereby causing the interruption of the primary circuit, the secondary circuit of the induction coil constituting an ignition means.
10. An igniter for gas engines, comprising an engine driven rotor mounted on trunnions, one of said trunnions being tubular, a cam mounted to slide in said tubular trunnion and having cam lugs projecting 20 through slots in the tubular trunnion, a stem connected with the cam, a cup contained within the tubular trunnion and having outwardly bent ears engaging the slots of the trunnion, a spring seated in the cup 25 and bearing on the cam for holding the cam in a normal position, a cap mounted on the end of the trunnion for limiting the movement of the cam and determining the normal position thereof, a head on the stem 30 forming an armature, an induction coil contained within the rotor and forming a magnet for attracting the armature and thereby withdrawing the cam from its normal position, and a switch contact for controlling 35 the primary circuit of the induction coil mounted in a position to be engaged by the cam lugs in the normal position of the cam and to be released thereby when the cam is moved by the attraction of the magnet for 40 opening the primary circuit of the induction coil, the secondary circuit of the induction coil constituting an ignition means.
11. An igniter for gas engines, comprising an engine driven rotor, trunnions on 50 which the rotor is mounted, a cam movably mounted on one of the trunnions, an induction coil carried by the rotor and constituting a magnet for moving the cam out of its normal position, a movably mounted 55 plate, a switch contact carried thereby for controlling the primary circuit of the induction coil and adapted to be engaged by the cam when the cam is in its normal position for closing the primary circuit, said cam being released from the switch contact 60 by the attraction of the magnet, the secondary circuit of the induction coil constituting an ignition means, and means for moving the plate for advancing or retarding ignition.
12. An igniter for gas engines, comprising a casing, a rotor journaled within the casing, an induction coil contained within the rotor, a cam carried by the rotor, switch contacts for controlling the primary circuit of the induction coil operated by the cam, a distributing block surrounding one 65 end of the rotor, contact segments carried by the distributing block adapted for connection with the spark plugs of the respective cylinders of the engine, a brush carried by the rotor and connected with the secondary coil of the induction coil and adapted to engage the contact segments, and a condenser contained in the space between the rotor and the casing and connected with the switch contacts.
13. An igniter for gas engines, comprising a casing, a rotor journaled within the casing, an induction coil contained within the rotor, a cam carried by the rotor, switch contacts for controlling the primary circuit of the induction coil operated by the cam, a distributing block surrounding one 70 end of the rotor, contact segments carried by the distributing block adapted for connection with the spark plugs of the respective cylinders of the engine, a brush carried by the rotor and connected with the secondary coil of the induction coil and adapted to engage the contact segments, and a condenser contained in the space between the rotor and the casing and connected with the switch contacts.
14. An igniter for gas engines, comprising a casing, a rotor journaled within the casing, an induction coil contained within the rotor, a cam carried by the rotor, switch contacts for controlling the primary circuit of the induction coil operated by the cam, a distributing block surrounding one 75 end of the rotor, contact segments carried by the distributing block adapted for connection with the spark plugs of the respective cylinders of the engine, a brush carried by the rotor and connected with the secondary coil of the induction coil and adapted to engage the contact segments, and a condenser contained in the space between the rotor and the casing and connected with the switch contacts.
15. An igniter for gas engines, comprising a casing, a rotor journaled within the casing, an induction coil contained within the rotor, a cam carried by the rotor, switch contacts for controlling the primary circuit of the induction coil operated by the cam, a distributing block surrounding one 80 end of the rotor, contact segments carried by the distributing block adapted for connection with the spark plugs of the respective cylinders of the engine, a brush carried by the rotor and connected with the secondary coil of the induction coil and adapted to engage the contact segments, and a condenser contained in the space between the rotor and the casing and connected with the switch contacts.
16. An igniter for gas engines, comprising a casing, a rotor journaled within the casing, an induction coil contained within the rotor, a cam carried by the rotor, switch contacts for controlling the primary circuit of the induction coil operated by the cam, a distributing block surrounding one 85 end of the rotor, contact segments carried by the distributing block adapted for connection with the spark plugs of the respective cylinders of the engine, a brush carried by the rotor and connected with the secondary coil of the induction coil and adapted to engage the contact segments, and a condenser contained in the space between the rotor and the casing and connected with the switch contacts.
17. An igniter for gas engines, comprising a casing, a rotor journaled within the casing, an induction coil contained within the rotor, a cam carried by the rotor, switch contacts for controlling the primary circuit of the induction coil operated by the cam, a distributing block surrounding one 90 end of the rotor, contact segments carried by the distributing block adapted for connection with the spark plugs of the respective cylinders of the engine, a brush carried by the rotor and connected with the secondary coil of the induction coil and adapted to engage the contact segments, and a condenser contained in the space between the rotor and the casing and connected with the switch contacts.
18. An igniter for gas engines, comprising a casing, a rotor journaled within the casing, an induction coil contained within the rotor, a cam carried by the rotor, switch contacts for controlling the primary circuit of the induction coil operated by the cam, a distributing block surrounding one 95 end of the rotor, contact segments carried by the distributing block adapted for connection with the spark plugs of the respective cylinders of the engine, a brush carried by the rotor and connected with the secondary coil of the induction coil and adapted to engage the contact segments, and a condenser contained in the space between the rotor and the casing and connected with the switch contacts.
19. An igniter for gas engines, comprising a casing, a rotor journaled within the casing, an induction coil contained within the rotor, a cam carried by the rotor, switch contacts for controlling the primary circuit of the induction coil operated by the cam, a distributing block surrounding one 100 end of the rotor, contact segments carried by the distributing block adapted for connection with the spark plugs of the respective cylinders of the engine, a brush carried by the rotor and connected with the secondary coil of the induction coil and adapted to engage the contact segments, and a condenser contained in the space between the rotor and the casing and connected with the switch contacts.

In testimony whereof, I affix my signature, in presence of two witnesses.

STEPHEN F. BRIGGS.
